UNITED STATES PATENT OFFICE.

HENRY GROSSMAN, OF NEW YORK, N. Y.

DESIGN FOR A POCKET-BOOK.

No. 39,417.

Specification for Design.

Patented July 14, 1908.

Application filed June 29, 1907. Serial No. 381,576. Term of patent 7 years.

To all whom it may concern:

Be it known that I, HENRY GROSSMAN, a citizen of the United States, residing at New York, in the county of New York and State of New York, have invented a new, original, and ornamental Design for Pocket-Books, of which the following is a specification, reference being had to the accompanying drawing, forming part thereof.

Figure 1 is a front view, and Fig. 2 is a rear view of pocket-book embodying my design.

The design represents a book A of general rectangular outline of or resembling alligator

skin, with an ornament B like an alligator foot or claw on its front face, and a hand-strap C on its rear face.

The principal feature of the design is the claw ornament B.

I claim:

The ornamental design for a pocket-book as shown.

HENRY GROSSMAN.
